PORTABLE COMMUNICATION AND CONTROL UNIT

Leon G. Barry, Danbury, Conn., and Harold Kimura,
New Rochelle, N.Y., assignors to Dictograph Products
Inc., Danbury, Conn., a corporation of Delaware

Filed June 22, 1964, Ser. No. 80,520

Term of patent 14 years

(Cl. D26—13)

FIGURE 1 is a perspective view of the top, front, and one side of a portable communication and control unit; and

We claim:

The ornamental design for a portable communication and control unit, as shown.
